PICKUP ARM CONTROL MECHANISM

Jerald D. Weaver, Fort Wayne, Ind., assignor to
 Farnsworth Television and Radio Corporation,
 a corporation of Delaware

Application October 17, 1942, Serial No. 462,341

6 Claims. (Cl. 274—15)

This invention relates to an improved automatic selective phonograph and more particularly to a mechanism for controlling the pickup arm thereof.

In conventional pickup arm control mechanisms there is provided a cam member having a plurality of cam surfaces for controlling the movement of the pickup arm. A plurality of levers are interposed between the pickup arm and the cam member and, when operated by the cam member, they function to elevate the pickup arm, swing it outwardly and control the movement of the pickup arm for positioning it in engagement with the initial groove of a record on the turntable. This type of mechanism includes a plurality of exposed, delicate parts which inherently require a considerable amount of service to be maintained in a satisfactory operating condition.

An object of the present invention is to provide in an automatic phonograph an improved pickup arm control mechanism which is simple in construction and effective in operation.

Another object of the present invention is to provide an enclosed substantially trouble-free pickup arm control mechanism.

In accordance with the present invention, there is provided an automatic phonograph comprising a turntable for supporting a record thereon, a pickup arm and a pedestal on which the pickup arm is mounted to swing vertically and horizontally into and out of engagement with the record on the turntable. There is also provided a driving mechanism for carrying out a record-changing cycle and a novel control device comprising a hydraulic mechanism connected to the driving mechanism and the pickup arm for elevating the pickup arm, swinging it outwardly beyond the periphery of the record and returning the pickup arm to the initial playing groove of the record on the turntable during a record-changing cycle.

For a better understanding of the invention, together with other and further objects thereof, reference is had to the following description, taken in connection with the accompanying drawing, and its scope will be pointed out in the appended claims.

In the accompanying drawing:

Fig. 1 is a side elevation, partly in section, of the pickup arm support and control mechanism in accordance with the invention.

Fig. 2 is a fragmentary view, partly in section, taken on line 2—2 of Fig. 1 showing the interior of the cylinder and the member therein for moving the pickup arm horizontally outwardly.

Fig. 3 is a fragmentary view, partly in section, taken on line 3—3 of Fig. 1 showing the mechanism for retarding the outward movement of the pickup arm and for swinging the pickup arm inwardly.

Referring particularly to Fig. 1 of the drawing, the invention here illustrated shows a pickup arm control mechanism which includes a base plate 10 for supporting a rotatable turntable 11 on which is shown a group of records 12, the uppermost record being in position for reproduction. The turntable 11 may be driven by any suitable conventional means, for example, such as disclosed in U. S. Patent No. 2,286,490, issued June 16, 1942. A pickup arm 14 is mounted to revolve in a horizontal plane on a pedestal 15 situated at one side of the turntable 11, as shown in Fig. 1. At the free end of the pickup arm 14, there is provided a pickup 17 with a stylus 18 which is adapted to cooperate with a record on the turntable 11 to reproduce it in the conventional manner.

As shown in Fig. 1, the pickup arm 14 may be pivotally mounted on a pin 20 supported by a bearing member 21 provided on a plate 22. The plate 22 is pivotally mounted on a pin 23 which is fixed to a plate 24. The plate 24 is connected to the upper end of a rotatable hollow shaft 26 in which a pin 27 is adapted to move vertically.

When the pickup arm 14 reaches the end of a record, the pin 27 (Fig. 1) is moved vertically into engagement with the plate 22 and moves the plate 22 in a clockwise direction (Fig. 1) on the bearing pin 23 thereby to move a screw 30 on the plate 22 in engagement with the underside of the pickup arm 14 to elevate the stylus 18 out of engagement with the record being played. Immediately after the pickup arm 14 is elevated, the shaft 26 is rotated to swing the pickup arm 14 horizontally outwardly to non-playing position. The mechanism for moving the pin 27 vertically and for rotating the shaft 26 will be described hereafter.

Pickup arm moving mechanism

The mechanism for moving the elements 26 and 27 is shown in Fig. 1 and comprises a hydraulic mechanism including a housing 32 providing a cylinder 33 in which a piston 34 fixed to the lower end of the pin 27 is adapted to be moved vertically to elevate the pin 27 and pickup arm 14. To the upper end of the cylinder 33 there is affixed a sleeve member 35 for supporting a bearing assembly 36 which rotatably supports the shaft 27. Concentric with the upper

end of the cylinder 33, there is provided a second cylinder 38. A baffle 39, shown in Fig. 2, is formed on the inner wall of the cylinder 38 to extend to the outer wall of the cylinder 33, and from the bottom of cylinder 38 to the cap member 40. A rotatable member 42 is fixed to the lower end of the shaft 26 and, as shown in Fig. 2, the member 42 has two vanes 43 and 44. The vane 44 is adapted to engage a stop 45 when the member 42 has been rotated a predetermined distance in a counterclockwise direction. When the member 42 is rotated, the shaft 26 and the pickup arm 14 are likewise rotated in a horizontal plane. Adjacent to the lower end of the cylinder 33, there is provided a third cylinder 47 (Fig. 1). The cylinder 47 is connected to the cylinders 33 and 38 by ports 49 and 48, respectively. The cylinder 47 and lower portion of the cylinder 33 are filled with a suitable fluid such as oil.

A piston 51, affixed to a connecting rod 52, is provided to reciprocate in the cylinder 47. When the piston 51 is moved to the right (Fig. 1), in a manner to be described hereafter, fluid from the cylinder 47 is forced through the openings 48 and 49 into the cylinders 33 and 38.

As shown in Fig. 1, a spring valve member 53 with a small port 54 is provided in the lower end of the cylinder 33 and is adapted in one position partly to close the opening 49. When the fluid is forced through the opening 49 from the cylinder 47 to the cylinder 33, the member 53 is moved away from the opening 49 to permit fluid to enter the cylinder 33 with less obstruction than provided to the cylinder 38 having the smaller opening 48. When the stylus of the pickup arm 14 is over the initial playing groove of a record, the vanes 43 and 44 are in the full line position (Fig. 2) and when the pickup arm has moved into the trip groove of a record, the vanes 43 and 44 are in the dotted line position shown in Fig. 2. When fluid is forced into the cylinder 38 in the area between the baffle 39 and the vane 43, the member 42 is rotated in a counterclockwise direction (Fig. 2) thereby to rotate the shaft 26 and the pickup arm 14 outwardly with respect to the turntable. The rotation of the shaft 26 is retarded by a spring member 55 (Figs. 1 and 3), one end of which is anchored to the shaft 26 and the other end of which is movable in a slot 56 provided in the cap member 40 (Fig. 3).

Since the fluid is permitted to flow faster into the cylinder 33 than into the cylinder 38, it will be evident that the piston 34 and the pickup arm 14 will be elevated before a sufficient amount of fluid is forced into the cylinder 38 to rotate the member 42. When the piston 34 is elevated sufficiently far to engage the lower end of the sleeve member 35 (Fig. 1) the pickup arm is elevated out of engagement with the record on the turntable. Thereafter, the piston 51 ceases to force fluid into the cylinder 33 and the spring valve member 53 moves back to partly close the opening 49, as shown in Fig. 1. As the piston 51 continues to move to the right, the fluid forced into the cylinder 38 rotates the member 42 in a counterclockwise direction (Fig. 2) thereby swinging the pickup arm outwardly. When the pickup arm 14 has been swung outwardly to a position approximately over the outer groove of a record on the turntable, the free end of the spring member 55 engages the lower end of the slot 56 (Fig. 3). Further rotary movement of the member 42 builds up tension in the spring member 55. When the piston 51 has completed its stroke, the vane

44 is moved into engagement with the stop 45 (Fig. 5) and the pickup arm is moved beyond the edge of the record on the turntable.

When the piston 51 is moved to the left (Fig. 1), 5 the fluid is gradually drawn from the cylinders 33 and 38. Thereupon, the spring member 56 rotates the member 42 in a clockwise direction (Fig. 2) to swing the pickup arm inwardly and the weight of the pickup arm on the pin 27 forces 10 the piston 34 downwardly. This horizontal and vertical movement of the pickup arm is controlled by the movement of the piston 51 as it draws the fluid from the cylinder 38 through the large opening 48 and from the cylinder 33 through the 15 small opening 54 in the member 53 (Fig. 1). From the above, it will be apparent that the fluid will be expelled from the cylinder 38 faster than it is expelled from the cylinder 33. Thus, 20 it will be evident that the pickup arm 14 will be moved inwardly under the biasing action of the 25 spring 55 to a position immediately over the initial groove of a record on the turntable before the weight of the pickup arm 14 on the pin 27 forces the piston 34 downwardly to the position shown in Fig. 1 where the stylus 18 of the pickup arm 14 engages the record on the turntable.

Driving mechanism for hydraulic control

30 This mechanism is best illustrated in Fig. 1 and includes a drive shaft 58 rotatably supported by a bracket 59 depending below the base plate 10. The shaft 58 may be driven by any suitable motor and gear mechanism known in the art. 35 U. S. Patent No. 2,018,881, issued October 29, 1935, discloses one form of this mechanism. The shaft 58 has affixed thereto a cam wheel 60 adapted to rotate therewith which is provided with two angular cam surfaces 61 and 62 and a 40 concentric cam surface 63.

A spring-biased lever 65 is pivotally connected as at 66, to the bracket 59 (Fig. 1). The upper end of the lever 65 has a rectangular aperture 67 which engages a pin 68 fixed to the connecting rod 52. A roller 70 fixed to the lower end of the lever 65 is biased into engagement with the cam wheel 60 by a tension spring 71 which has one end anchored to the pin 72 fixed to the bracket 59 and the other end engaging the edge 50 of the lever 65, as shown in Fig. 1.

In operation, after the record on the turntable 11 is reproduced and the stylus 18 moves into the trip groove, a tripping mechanism, such as disclosed in U. S. Patent No. 2,018,881, issued October 29, 1935, may be incorporated in this apparatus to initiate the rotation of the shaft 58 through a cycle of operation. When cam wheel 60 begins to rotate, the cam surface engages the roller 70 to move the lever 65 in a clockwise direction 45 (Fig. 1) against the biasing action of the spring 71. As the lever 65 moves, the left-hand edge of the aperture 67 engages the pin 68 and moves the rod 52 and the piston 51 to the right against the biasing action of a spring 69 (Fig. 1). The energy stored in the spring 69 is of such proportion that only a force slightly greater will be required to overcome the frictional engagement between the piston 51 and the cylinder 47.

70 The piston 51, in moving to the right (Fig. 1) forces fluid into the cylinders 33 and 38 to elevate the pickup arm and swing it horizontally beyond the edge of the record on the turntable in the manner heretofore described. While the roller 70 is in engagement with the cam surface 63, the

piston 51 is maintained near the right-hand end of the cylinder 47 and the pressure in the cylinders 33 and 38 holds the pickup arm elevated above and beyond the record on the turntable. When the cam surface 62 engages the roller 70, the spring 71 moves the lever 65 in a clockwise direction (Fig. 1) to move the right-hand edge of the aperture 67 into engagement with the pin 68 and thereby moves the rod 52 and the piston 51 to the left (Fig. 1). The piston 51, in moving, permits the tension spring 55 to rotate the member 42 in a clockwise direction to swing the pickup arm inwardly over the outer groove of the record on the turntable and thereafter the piston 34 gradually lowers the stylus 18 into engagement with the record on the turntable 11. By the time the cam wheel completes a cycle of operation, the lever 65 is moved back to the position shown in Fig. 1. However, due to the length of the aperture 67, it is evident that the lever 65 moves in a counter-clockwise direction a predetermined distance before it functions to move the rod 52 and the piston 51 to the left relative to the cylinder 47. Therefore, when the lever reaches its normal position shown in Fig. 1, it is evident that the piston 51 is not returned to the normal position, and the pickup arm 14 ceases to be moved inwardly by the movement of the piston 51 and the tension of the spring 55. With the piston out of its normal position, it is evident that a portion of the fluid remains in the cylinder 38.

In order for the mechanism to function properly during the succeeding cycle of operation, it is necessary to move the piston 51 back to the position shown in Fig. 1. To do this, only a force slightly greater than that of the spring 69 needs to be supplied. This added force is developed by the movement of the pickup arm as it reproduces a record. As the pickup arm moves inwardly, the vane 43 is moved from the full line to the dotted line position (Fig. 2). This movement of the vane 43 forces the fluid remaining in the cylinder 38 into the cylinder 47. This force cooperates with the spring 69 to move the piston 51 back to the position shown in Fig. 1.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In an automatic phonograph comprising a rotatable turntable for supporting a record, a reproducing means including a pickup arm, a rotatable member on which said pickup arm is mounted to move vertically and horizontally into and out of play engagement with a record on said turntable, an elevating member movable vertically in said rotatable member and adapted to elevate said pickup arm out of engagement with said record on said turntable, reciprocable hydraulic means for operating said elevating member for elevating said pickup arm, rotatable hydraulic means for operating said rotatable member and swinging said pickup arm horizontally beyond the record on said turntable and returning said pickup arm into engagement with the initial groove of said record on said turntable, and operating means for controlling said hydraulic means.

2. In an automatic phonograph comprising a rotatable turntable for supporting a record, a reproducing means including a pickup arm, a hydraulic mechanism including a first cylinder, a rotatable member adapted to rotate therein and having a shaft portion on which said pickup arm is pivotally mounted to move vertically and horizontally into and out of engagement with a record on said turntable, a second cylinder, a piston movable in said second cylinder to elevate said pickup arm, a third cylinder connected to said first and second cylinders by openings and filled with a fluid and a piston movable in one direction in said third cylinder to force said fluid into said first and second cylinders for elevating said pickup arm and rotating said member to swing said pickup arm beyond the record on said turntable and movable in the opposite direction for returning the pickup arm into engagement with the beginning of the record on said turntable, and operating means connected to said piston in said third cylinder.

3. In an automatic phonograph comprising a rotatable turntable for supporting a record, a reproducing means including a pickup arm, a pedestal, a rotatable tubular shaft associated with said pedestal and pivotally supporting said pickup arm to move vertically and horizontally thereon into and out of playing engagement with a record on said turntable, a bearing member for rotatably supporting said rotatable shaft, a pin movable vertically in said shaft for elevating said pickup arm, a hydraulic mechanism including a first cylinder, a piston connected to said pin and movable in said first cylinder for elevating said pin and said pickup arm, a second cylinder, a member fixed to said rotatable shaft and rotatable in said second cylinder, a third cylinder connected to said first and second cylinders by openings and filled with a fluid and a piston movable in one direction in said third cylinder for forcing said fluid through said openings into said first and second cylinders for elevating said pickup arm and rotating said shaft to swing said pickup arm horizontally beyond the edge of said record on said turntable and adapted when moved in the opposite direction to draw said fluid from said first and second cylinders and control the inward movement of said pickup arm and the return movement of said piston in said second cylinder to properly position said pickup arm in engagement with the beginning of said record on said turntable, and operating means connected to said piston in said third cylinder.

4. In an automatic phonograph comprising a rotatable turntable for supporting a record, a reproducing means including a pickup arm, a pedestal, a rotatable tubular shaft associated with said pedestal and pivotally supporting said pickup arm to move vertically and horizontally thereon into and out of playing engagement with a record on said turntable, a bearing member for rotatably supporting said rotatable shaft, a pin movable vertically in said shaft for elevating said pickup arm, a hydraulic mechanism including a first cylinder, a piston connected to said pin and movable in said first cylinder for elevating said pin and said pickup arm, a second cylinder, a member fixed to said rotatable shaft and rotatable in said second cylinder, a third cylinder connected to said first and second cylinders by openings and filled with a fluid and a piston movable in said third cylinder for forcing said fluid into said first and second cylinders when moved in one direction for elevating said pickup arm and

rotating said shaft to swing said pickup arm horizontally beyond the edge of said record on said turntable and when moved in the opposite direction for drawing said fluid from first and second cylinders thereby controlling the inward movement of said pickup arm and the return movement of said piston in said second cylinder to properly position said pickup arm in engagement with the beginning of said record on said turntable, and operating means connected to said piston in said third cylinder.

5. In an automatic phonograph comprising a rotatable turntable for supporting a record, a reproducing means including a pickup arm, a pedestal, a rotatable tubular shaft associated with said pedestal and pivotally supporting said pickup arm to move vertically and horizontally thereon into and out of playing engagement with a record on said turntable, a bearing member for rotatably supporting said rotatable shaft, a pin movable vertically in said shaft for elevating said pickup arm, a hydraulic mechanism including a first cylinder, a piston connected to said pin and movable vertically in said first cylinder for elevating said pin and said pickup arm, a second cylinder, a member fixed to said rotatable shaft and rotatable in said second cylinder, a third cylinder connected to said first and second cylinders by openings and filled with a fluid, a piston movable in said third cylinder for forcing said fluid into said first and second cylinders for elevating said pickup arm and rotating said shaft to swing said pick-

10 up arm horizontally beyond the edge of said record on said turntable and for controlling the inward movement of said pickup arm to a point immediately over the beginning of a record on said turntable, a valve member in said second cylinder for controlling the lowering of said piston in said second cylinder to properly position said pickup arm in engagement with the beginning of said record on said turntable, a spring member connected to said shaft and said hydraulic means for swinging said pickup arm inwardly toward the center of the record on said turntable, and operating means connected to said piston in said third cylinder.

15 6. In an automatic phonograph comprising a rotatable turntable for supporting a record, a reproducing means including a pickup arm, means for supporting said pickup arm whereby it may move vertically and horizontally into and out of playing engagement with a record on said turntable, a reciprocable fluid operated means connected to said pickup arm for elevating it, a rotatable fluid operated means connected to said pickup arm for swinging it horizontally beyond the edge of the record on said turntable and returning said pickup arm into engagement with the initial groove of the record on said turntable during a record changing cycle, hydraulic control means for operating both said fluid operated means, and operating means for actuating said hydraulic control means.

JERALD D. WEAVER.
